BATHING POOL

William G. Dobbs, Auburn, N. Y.

Application May 10, 1934, Serial No. 725,000

9 Claims. (Cl. 4—173)

This invention relates to improvements in baths and pertains particularly to an improved tub structure.

The primary object of the present invention is to provide an improved form of bath which is in the nature of a pool whereby the bather may step down into the water containing area from the floor level of the room in which the bath is located, and may stand or sit in the water while bathing.

A further object of the invention is to provide an improved bathing pool in which the bather steps down in entering the pool and in which means is provided whereby the upper part of the pool may be closed so that the bather will be shielded from the view of others in the room in which the pool is installed.

A still further object of the invention is to provide an improved bathing pool of novel construction in the arrangement of a seat in the pool and of conveniently arranged corner steps whereby the bather may conveniently enter the pool by degrees.

Still another object of the invention is to provide an improved bathing pool structure having novel shower means associated therewith, one novel feature of said shower means including a combined hand rail and bar spray.

Another novel feature of the invention resides in the provision in a pool bath of the above described character, of means whereby a supply of sea salt or other chemical may be kept at hand and conveniently introduced into the bath when desired.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in perspective of a corner of a room showing the installation of a structure of the character embodying the present invention.

Figure 2 is a vertical sectional view through the structure and through adjacent portions of the room wall and floor.

Figure 3 is a horizontal section taken on the line 3—3 of Figure 2.

Figure 4 is a vertical section taken on the line 4—4 of Figure 2.

Referring to the drawings wherein like numerals of reference designate corresponding parts throughout the several views, the bath embodying the present invention is illustrated in installed position, Figure 1 illustrating the portion of the bath which will be on view in a room in which it is installed, the floor of which room is indicated by the numeral 1, while two of the walls thereof are indicated by the numerals 2 and 3. While the bath may be installed in the center of a room space, it is here illustrated as being installed in the angle formed by two joining walls.

The pool structure is indicated as a whole by the numeral 4 and this comprises the cast shell which is made up of the vertical back wall 5, the front wall 6 and the top and bottom walls 7 and 8, respectively. As illustrated, the front wall curves upwardly and rearwardly from a point substantially midway between the top and bottom walls and this upwardly and rearwardly curving section has the entrance 9 formed therethrough. At each side of this entrance opening 25 to the bath are hand rails 10 which the bather may hold while stepping into the bath and at the lower part of the entrance is a forwardly and upwardly projecting sill 11 which projects above the floor 1 of the room in which the bath 30 is installed.

Cast integral with the body of the bath about the mid-section thereof is the outwardly projecting flange 12 by which the bath is mounted upon supporting floor beams or joists, and extending upwardly from this flange upon either side of the bath structure and across the top thereof is a second flange 13 for attachment to vertical and horizontal studding of the wall in which the structure is disposed.

Substantially midway between the bottom and the sill of the entrance opening 9, the front wall 6 of the structure is inset to form the centrally located seat shelf 14 and upon either side of this seat shelf, the body of the structure is molded 45 to form the corner shelf 15 which is at a higher elevation than the seat shelf and which is bordered by the upstanding flange 16. At a lower elevation than the seat shelf 14 and above the floor or bottom 8, there is formed in each 50 front corner of the structure the corner step 17 upon which the bather steps when entering the pool.

Cast integral with the back and side walls just above the bottom 8, are the shielded water 55

inlet openings 19 which have leading thereto the pipe 20.

Extending across each side wall and across the back wall 5 is a hand rail 21. This rail is of tubular construction and is provided with a plurality of fine water outlet openings 22 and is connected with a pipe coupling 23 which is disposed outside the back wall 5 for connection with a water supply line. This hand rail and spray is disposed at an elevation in the pool substantially level with the floor of the room in which the unit is installed and directly below this rail is the overflow outlet 24 which leads to a suitable waste pipe through the usual connections. The waste pipe for the unit is indicated generally by the numeral 24 and this also has leading thereto the pipe 25 which opens into the pool through the bottom thereof so that the pool may be drained by this means.

20 At a substantial distance above the hand rail
bar spray structure 21 is a ring shower spray 26
which is joined with the usual coupling 27 at the
back of the pool, and suspended from the top
wall 7 is an overhead shower unit 28 which is
25 also connected with an outside coupling 29. The
couplings leading to the shower 28, the spray
devices 21 and 26 and the inlets 19, are all joined
with a suitable water pipe line and the flow of
water to each of these units may be separately
30 controlled. In addition, the water from the
usual hot and cold lines may be passed through
a suitable mixing faucet before reaching the
branches which lead to the several shower units
and the bottom inlets so that the temperature of
35 the water may be accurately controlled.

35 The several valves and the pipe lines leading to the spray and inlet units have not been illustrated for the reason that such features are ordinary in plumbing fixtures and are, therefore, 40 well known to those familiar with the art. It is contemplated, however, to have the handle elements by which the several valves may be controlled, mounted in the pool upon a central panel such as is indicated by the numeral 30 and which 45 is preferably disposed upon the back wall 5 at a convenient elevation. Here may be grouped all of the valve control handles and also the handles necessary for opening the vent or drain pipe 25.

50 In addition to the units for introducing wa-
ter into the pool, there may be provided at any
suitable location outside of the pool, a receptacle
51 having a pipe line 32 leading to a suitable in-
let opening 33 at the bottom of the pool, and this
55 receptacle may be employed to contain salt or
any other chemical which may be desired for
use in connection with a bath. This pipe line 32
may also be controlled by a suitable valve hav-
ing a control lever therefor located on the panel
60 30 with the other valve control units.

In order that water from the overhead shower may be prevented from escaping through the entrance opening 9 and also that the bather may be shielded from the view of anyone else in the room in which the fixture is installed, there may be mounted upon a roller of suitable type such as indicated generally by the numeral 34, a curtain 35 of water-proof material. This roller is mounted at the top of the fixture so that the curtain 70 may be drawn down over the opening 9.

From the foregoing, it will be readily apparent that the present invention provides a novel bathing fixture in which a bather may conveniently sit or stand while bathing and also a fixture which may be used without danger, as the bather is not

required to step over any high walls but merely steps down into the same in the same manner as entering an outdoor bathing pool. The depth of the pool is such that when the same is filled to capacity, the bather, when seated upon the seat shelf 14, will be completely immersed in the water up to the neck.

What is claimed is:—

1. A bathing pool, comprising an elongated receptacle disposed in vertical position and having top, bottom and side walls, one of said side walls having an entrance opening through the upper portion thereof, means for introducing water into the receptacle, drain means in the bottom wall of the receptacle, and a seat in the form of a step disposed at an elevation between the lower part of the said wall opening and the bottom of the receptacle. 10 15

2. A bathing pool, comprising an elongated vertically disposed receptacle having top, bottom and side walls, one of said side walls having an entrance opening therethrough, the lower side of which is disposed substantially midway between the top and bottom walls of the receptacle, a seat in the form of a step disposed beneath the lower side of said entrance opening, a step disposed adjacent one side wall at one end of the seat and at an elevation beneath the seat, a drain opening in the bottom of the receptacle, and means for introducing water into the receptacle. 30

3. A bathing pool, comprising an elongated vertically disposed receptacle having front, back, side, top and bottom walls, said front wall being curved from a point substantially intermediate the top and bottom walls, upwardly and rearwardly and having an entrance opening through said curved portion, said front wall at a point beneath the entrance opening being inset to form a seat step extending transversely of the receptacle, means at each side of the seat step forming a shelf at an elevation above the step, means adjacent one side wall forming a step at an elevation below the seat step, drain means for the receptacle, and means for introducing water into the receptacle. 45

4. A bathing pool, comprising an elongated vertically disposed receptacle having top, bottom, front, back and side walls, said front wall being curved upwardly and rearwardly from a point substantially midway between the top and bottom walls and having an entrance opening through the curved portion, said front wall beneath said entrance opening being inset to form a step seat, means forming a shelf across the corner between each side wall and the front wall at an elevation between the top of said seat and the lower part of the entrance opening, means forming a step across the corner between each side wall and the front wall at an elevation below the top of said seat, drain means for the receptacle, and means for introducing water into the receptacle.

5. A bathing pool, comprising an elongated vertically disposed receptacle having top, bottom, front, back and side walls, said front wall being curved upwardly and rearwardly from a point substantially midway between the top and bottom walls and having an entrance opening through the curved portion, said front wall beneath said entrance opening being inset to form a step seat, means forming a shelf across the corner between each side wall and the front wall at an elevation between the top of said seat and the lower part of the entrance opening, means forming a step across the corner between each side wall and the front wall at an 65 70 75

elevation below the top of said seat, drain means for the receptacle, means for introducing water into the receptacle, a hand rail extending vertically along each side of said entrance opening, and a curtain mounted at the upper side of the entrance opening and adapted to be drawn downwardly thereover.

6. In a structure of the character described, a water receptacle, drain means therefor, and a combined hand rail and spray bar mounted with in the receptacle.

7. A bathing structure of the character described, comprising an elongated vertically disposed receptacle having one wall provided with an entrance opening above a line lying substantially midway between the ends of the receptacle, seat means within the receptacle below the lower side of the entrance opening, drain means for the receptacle, a tubular hand rail mounted in the receptacle, said rail having a plurality of small diameter apertures opening through the wall thereof, and means for coupling a water pipe to the hand rail whereby a water spray may be discharged therefrom.

25 8. A bathing structure, comprising an elongated vertically disposed receptacle having an entrance opening formed through one vertical

wall above the transverse medial portion thereof, drain means for the receptacle, means for introducing water into the receptacle, a second receptacle exterior to the first, and a pipe connection between the lower part of the second receptacle and the lower part of the first receptacle whereby material contained in the second receptacle may be introduced into the first receptacle.

9. A bath tub, comprising a body of a height 10 materially greater than the width or depth from front to rear and having top, bottom, front, rear and side walls, said front wall being curved from a point substantially midway between the top and the bottom toward the rear of the structure 15 and having an entrance opening therein, a flange upstanding across the entrance opening at the bottom edge thereof and set forwardly of the adjacent portion of the front wall, means facilitating entrance into the tub constituting a step 20 within the tub beneath the entrance opening, means for discharging water into the tub, drain means for the tub and a roller curtain mounted above the entrance opening to be drawn down over the same and having a bar across its lower 25 edge adapted to position behind said flange.
